UNITED STATES PATENT OFFICE.

LÉON ABEL CELER LETOMBE, OF PARIS, FRANCE.

APPARATUS FOR AUTOMATICALLY STARTING EXPLOSIVE-MOTORS OR THE LIKE.

No. 857,639.

Specification of Letters Patent.

Patented June 25, 1907.

Application filed October 4, 1906. Serial No. 337,420.

To all whom it may concern:

Be it known that I, LÉON ABEL CELER LETOMBE, a citizen of the Republic of France, residing at Paris, France, have invented Improvements in Apparatus for Automatically Starting Explosive-Motors or the Like, of which the following is a specification.

The present invention relates to a compressed fluid distributing device employed in connection with means for automatically starting explosion motors or the like and comprises the several novel elements and combinations of elements hereinafter fully described and particularly pointed out in the appended claims.

In the accompanying drawing wherein like reference characters refer to like parts throughout the several views, Figure 1 is a vertical central longitudinal section showing a compressed fluid distributing device; Fig. 2 is a transverse section thereof, parts being removed, and Fig. 3 shows the valve proper of such device in elevation. Fig. 4 is a detail view of a gas inlet valve, for a motor cylinder. Fig. 5 is a similar view to Fig. 3 showing another construction of distributing device.

1 is a cylindrical casing in one end of which is formed as many suitably arranged orifices 2 as there are cylinders to be supplied, in the example under consideration four such passages are shown.

Arranged to slide and rotate in the casing 1 is a disk valve 3 formed with an arc port 4 of the proper length for regulating the time of admission of the gases under pressure into a cylinder. This valve slides at one end on a hollow rod 5 passing through the casing 1 and forming a shaft, and at the other end in a central compressed gas passage 6. The shaft 5 is connected to the valve 3 by means of a slot in the shaft engaging a cotter 14 of the valve boss, as shown in the drawings, so that the valve moves with the shaft.

45 A spring 7 located in the hollow shaft and bearing against the cotter 14 at one end and against a transverse pin at the other normally prevents the valve 3 moving relatively to the shaft 5.

50 A chain wheel 8 at the end of the shaft 5 is driven by a chain at a speed corresponding to that of the motor valve actuating shafts. The chain wheel 8 is fixed on the shaft in such angular position that upon rotation the

valve 3 allows the compressed gas to pass into the cylinders during the periods corresponding to the working strokes.

The action is as follows:—When the compressed gas is admitted into the casing 1 the valve 3 is pushed forward by its rear extension 9 acting as a piston until the front face of the valve bears against the adjacent end of the casing, owing to its inertia, the compressed gas passing freely through the port 4 to the cylinder 10 (Fig. 4), of which the working stroke is about to begin. In order to prevent shock when the valve 3 comes into contact with the casing end its cylindrical extension forms a dash pot on the hollow rod 5 which only communicates with the atmosphere through a small hole 11. The motor starts immediately the valve, driven by the general movement of the engine, turns while remaining held in contact with the casing end by the pressure of the compressed gases which are thus distributed in turn to all the cylinders during their working strokes. The consumption of compressed gas is automatically suspended as soon as the first explosions in the cylinders are produced at a pressure higher than that of the compressed gases. With this object the compressed gas in order to reach the cylinders passes through small non return valves 12, Fig. 4, opening toward the interiors of the cylinders and which naturally are held down on their seats if the pressure in the cylinders is higher than the pressure of the compressed gas coming from the casing 1. As soon as the system of pipes is again placed in communication with the atmosphere, the pressure falls in the valve casing 1 and the valve 3 being pushed back by the internal spring 7 of the rod 5 once more assumes its inoperative position in which it may rotate without its face rubbing on the end of the casing.

Instead of a disk valve 3 covering and uncovering the ports 2 there may be employed for this purpose a plate 3 carrying a cam 4, as shown in Fig. 5. This plate is adapted to slide on the driving shaft 13 which is formed with a square driving end 14 and also with an axial hole 11 communicating with the atmosphere.

The plate 3 is provided with a rearward extension or boss 9 which in the state of rest closes the compressed gas passage 6 under the action of the spring 7. The compressed

gas entering the casing 1 through the passage 6 passes into the annular space 16, through the gas conduit 17. When the compressed gas enters the casing 1 through the passage 6 the plate 3 is pushed forward on the shaft 13 and is held in this position by the difference of pressure that exists on the two faces of the plate 3 owing to the perforation in the shaft. In this position one of the double-seat valves 2 corresponding to a cylinder in its working period, is raised and the motor starts working, the cam 4 raising in succession the whole of the valves 2. When the motor is running at its normal speed and the pressure is allowed to fall, the spring 7 immediately pushes the plate 3 out of action automatically.

In all arrangements the distributing apparatus is adapted to be so operated by hand or foot as to enable the compressed gas to be admitted to the motor starting means or to place such means in communication with the atmosphere.

What I claim is:—

1. In apparatus for automatically starting explosion motors or the like, a compressed fluid distributing device comprising the combination with a casing having ports leading to the motor, of a valve adapted to have reciprocal and rotary motion within said casing for the purpose of opening and closing said ports alternately to the admission of compressed fluid.

2. In apparatus for automatically starting explosion motors or the like, a distributing device interposed between the source of compressed fluid supply and the motor, said distributing device comprising a casing having the same number of ports as there are motor cylinders to be supplied with compressed fluid, and an apertured valve having reciprocal and rotary motion within said casing and being adapted to alternately open and close the ports in said casing to the admission of compressed fluid.

3. In apparatus for automatically starting explosion motors or the like, a distributing device comprising a ported casing, a bored spindle revolvably mounted therein and a valve carried by said spindle and adapted to have reciprocal and rotary motion within said casing.

4. In apparatus for automatically starting explosion motors or the like, a distributing device comprising the combination with a casing having ports corresponding in number to the number of cylinders to be supplied with compressed fluid, of a hollow shaft extending transversely through a portion of said casing, means for revolving said shaft and a valve mounted upon said shaft and adapted to have reciprocal and rotary motion within said casing.

5. In apparatus for automatically starting explosion motors or the like, a distributing

device comprising the combination with a casing having a port for the admission of compressed fluid and separate ports for the passage of compressed fluid to the motor cylinders, of a valve interposed between said admission and emission ports, said valve being designed to have reciprocal and rotary motion within the casing for the purpose of alternately opening and closing said emission ports to the flow of compressed fluid.

6. In apparatus for automatically starting explosion motors or the like, the combination with a casing having a port at one end for the admission of compressed fluid and ports at the opposite end for permitting the compressed fluid to pass into the motor cylinders, of a valve adapted to have reciprocal and rotary motion within said casing and interposed between the admission port and emission ports for the purpose of alternately opening and closing said emission ports to the flow of compressed fluid.

7. In apparatus for automatically starting explosion motors or the like, a distributing device comprising the combination with a casing having a contracted end containing a compressed fluid admission port, of a shaft adapted to revolve within bearings formed by said casing, means for revolving said shaft, a valve mounted upon said shaft to have reciprocal and rotary motion within the casing, said valve being adapted to be forced within the casing upon the admission of compressed fluid thereto and to be returned to normal inoperative position upon exhaustion of compressed fluid from the casing.

8. In apparatus for automatically starting explosion motors or the like, a distributing device comprising a casing provided at one end with a port for the admission of compressed fluid, and at its opposite end with ports for leading said compressed fluid to motor cylinders, of a valve within said casing having an arc port cut therein and means whereby said valve may have reciprocal and rotary motion within said casing.

9. In apparatus for automatically starting explosion motors or the like, a distributing device comprising the combination with a casing having a compressed fluid admission port at one end and ports at the opposite end for leading compressed fluid to motor cylinders, of a shaft extending partially through said casing, and a valve mounted upon said shaft and adapted to have reciprocal and rotary motion within said casing, said valve being provided with a boss adapted to fit within the walls forming said compressed fluid admission port.

10. In apparatus for automatically starting explosion motors or the like, a distributing device comprising the combination with a casing having an admission port at one end and emission ports at its opposite

end, of a hollow shaft journaled in said casing, a valve mounted upon said shaft, and a spring contained in said shaft.

11. In apparatus for automatically starting explosion motors or the like, a distributing device comprising the combination with a casing having an admission port at one end and emission ports at its opposite end, of a valve adapted to have reciprocal and rotary motion within said casing, said valve embodying means for alternately opening and closing said emission ports to the flow of compressed fluid.

12. In apparatus for automatically starting explosion motors or the like, the combination with a distributing device comprising a casing having emission ports, of motor cylinders communicating with said emission ports, a valve adapted to rotate and reciprocate for alternately opening and closing said emission ports, and a valve in each said cylinder for closing the same when the pressure therein is greater than the pressure in said casing.

13. In apparatus for automatically starting automobile motors or the like, the combination with a distributing device comprising a casing having emission ports, a valve designed to have reciprocal and rotary motion within said casing for alternately opening and closing said ports to the admission of compressed fluid, a cylinder in communication with each said emission port, and a valve interposed between each cylinder and

35
der and emission port for closing said cylinder when the pressure therein is greater than the pressure in said casing.

14. In apparatus for automatically starting automobile motors or the like, the combination with a distributing device comprising 40 a casing having emission ports, a motor cylinder in communication with each said port, and a valve adapted to have reciprocal and rotary motion within said casing, said valve being provided with means for alternately opening and closing said ports to the admission of compressed fluid to said cylinders.

15. In apparatus for automatically starting automobile motors or the like, the combination with a distributing device comprising a casing having a compressed fluid admission port at one end and emission ports at its opposite end, a motor cylinder in communication with each said emission port, 55 a shaft journaled in said casing, a valve adapted to reciprocate and rotate upon said shaft within said casing, and means for revolving said shaft, said valve embodying means for alternately opening and closing 60 the said emission ports to the admission of compressed fluid to said motor cylinders.

Signed at Paris, France, this 25th day of September 1906.
